PHILIP L. O'DONNELL, OF NORWOOD, OHIO

PROCESS OF MAKING SHOES

Application filed September 19, 1929. Serial No. 393,792.

My invention relates to processes of making shoes, and particularly to the step in the process involving the attachment of the counter within the shoe.

5 In the manufacture of shoes having counters, whether they be of leather or fiber, it has been customary, prior to the insertion of the counter within the shoe, to coat the counter with glue, cement or paste, and then 10 insert it between the lining and the shoe upper in the heel portion of the shoe. The counter extends up toward the shank where it gradually flares away from the top edge so as not to interfere with the free flexibility of the 15 shoe in the shank portion.

If the glue, cement or paste is not applied entirely evenly, it is likely to form lumps which cause an uneven surface on the lining of the shoe, which is uncomfortable to the 20 wearer, and also tends to form a spot where the lining will tend to wear out. Further, the process is dirty and tedious. It is my object to obviate the difficulties in gluing, 25 cementing or pasting the counters and afterwards inserting them in the shoes, by treating the counters with a heat-plastic material and then shortly prior to the insertion within the shoe, to pass the counter, preferably on a belt, through a heating oven so that the heat, 30 plastic cement is rendered adhesive only shortly before the counter is inserted in the shoe.

In my co-pending application Serial No. 393,793 of September 19, 1929, I have proposed the dipping of a shoe counter in a cellulose-hydrate solution which increases the tensile strength of the counter and makes it impervious to moisture or alkaline or acid reactions. As a further step in the way of a 40 refinement of this process, I may, in addition to the cellulose-hydrate treatment, dip the counter in a gutta-percha tetra-chloride mixture. The gutta-percha tetra-chloride mixture forms an excellent heat plastic cement, 45 so that the manufacturer, before assembling the counters between the lining and upper, heats the counter so as to render the cement adhesive. The counter is then inserted in the shoe and the shoe is then formed on the 50 last in the usual manner.

The above and other objects to which reference will be made in the ensuing disclosure I accomplish by the treatment which will hereinafter be described.

Referring to the drawings:—

Figure 1 is a perspective view of a shoe counter.

Figure 2 is a section taken along the lines 2—2 in Figure 1.

The shoe counter has sides 1, inwardly flanged attachment portions 2, and top edges 3.

While my process may be employed with any type of counter, I prefer to use it with a fiber counter.

As has been stated, I may first dip selected portions of the counter in a cellulose-hydrate solution and allow it to dry, or I may dispense with this cellulose-hydrate treatment altogether, the use of the cellulose-hydrate comprising an invention distinct from my treatment of the counter with heat plastic material.

The counter manufacturer first forms a fiber blank, and then, under great pressure, forms the counter to its desired shape. After the counter is formed and is thoroughly dry, it may be dipped in a gutta-percha solution in carbon tetra-chloride mixture which forms a thin layer 4 over the inner and outer surfaces of the counter. The shoe manufacturer takes the counters, which, at the time of shipment are thoroughly dry, and exposes them to some source of heat to soften the heat plastic material shortly before the counters are inserted in the shoes, and before the shoes are formed on the last.

There is a great saving in the labor required in the inserting of the counters within the shoes, as no application of glue is required, and the shoe counters can be advanced to a group of operators in a constantly moving stream which does not require any extra movements except the insertion of the counter within the shoe. Having been previously heated, the shoe counter will immediately become adhesive and stick firmly in place within the shoe, and the step of forming on the last will make a thor-

oughly good sealing job which will not tend to bend out of shape or crack.

While the particular type of heat plastic cement may be varied, and the particular method of heating the counters by passing them through a heat chamber on a belt may be substituted by heating them in other ways, it should be understood that I consider within the scope of my invention the pretreatment of a shoe counter with a heat-plastic material which is then allowed to dry, and subsequently, prior to inserting the counter in the shoe, the heat-plastic cement is heated so that it may be secured firmly in place within the shoe.

Having thus described my invention, what I claim as new and desire to secure by Letters Patent, is:-

In the art of making shoes, the steps which consist in treating the shoe counters with gutta-percha dissolved in carbon teta-chloride, allowing the mixture to dry, and, prior to the insertion of the counter within the shoe, heating the counter so as to make the gutta-percha teta-chloride mixture adhesive, and then, while in such condition, inserting the counter within the shoe.

PHILIP L. O'DONNELL.
